(57) **CLAIM**

The ornamental design for the ostomy bag cover, as shown.

DESCRIPTION

FIG. 1 is an isometric view of the ostomy bag cover.

FIG. 2 is a front elevation view of the ostomy bag cover.

FIG. 3 is a rear elevation view of the ostomy bag cover; and, FIG. 4 is a front elevation view of the ostomy bag cover with the flap folded over.

The broken lines along the perimeter of the opening and the lower edges of the cover represent stitching in all the figures.
